(57) **CLAIM**

The ornamental design for connection station for drug delivery devices, as shown and described.

DESCRIPTION

FIG. 1 is a perspective view of a connection station for drug delivery devices in a closed position.

FIG. 2 is another perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a left side elevation view thereof.

FIG. 8 is a right side elevation view thereof.

FIG. 9 is a perspective view of the connection station for drug delivery devices in an open position.

FIG. 10 is another perspective view thereof.

FIG. 11 is a top plan view thereof.

FIG. 12 is a perspective view of the connection station for drug delivery devices connected to a drug delivery device.

FIG. 13 is another perspective view thereof.

FIG. 14 is a front elevation view thereof.

FIG. 15 is a rear elevation view thereof.

FIG. 16 is a top plan view thereof.

FIG. 17 is a bottom plan view thereof.

FIG. 18 is a left side elevation view thereof; and,

FIG. 19 is a right side elevation view thereof.

The broken lines depict unclaimed environmental subject matter.
